UNITED STATES PATENT OFFICE.

MILTON H. SHOENBERG, OF SAN FRANCISCO, CALIFORNIA, ASSIGNOR TO FREDERICK C. MORGAN, OF SAN FRANCISCO, CALIFORNIA.

ELECTRIC HEATING DEVICE.

1,091,774.

Specification of Letters Patent. Patented Mar. 31, 1914.

Application filed November 6, 1912. Serial No. 729,902.

To all whom it may concern:

Be it known that I, MILTON H. SHOENBERG, a citizen of the United States, residing in the city and county of San Francisco and 5 State of California, have invented certain new and useful Improvements in Electric Heating Devices, of which the following is a specification.

The hereinafter described invention relates to a simple, effective, inexpensive and durable open mouth device for quickly heating water placed therein for use generally, although the device is more particularly designed for the heating of the contents of an 10 auxiliary vessel placed within the outer vessel and partly submerged therein, as, for instance, the heating of the food or milk contained in a bottle, the contents of which is used for the feeding of babies; the object 15 of the invention being the providing of means for positively and quickly raising the temperature of liquid or water placed in the open mouth vessel, the providing of hand actuated spring controlled means for automatically cutting off the electric current on 20 the removal of pressure therefrom, and in the production of simple and effectual means for forming a sealed joint between the lower end of the vessel and the base support therefor.

To comprehend the invention, reference should be had to the accompanying drawings, wherein—

Figure 1 is a side elevation of the improved heating device, with an auxiliary vessel mounted therein. Fig. 2 is a vertical sectional view of the improved heating device with the auxiliary vessel mounted therein. Fig. 3 is a cross sectional view taken on line $x-x$ —Fig. 1 of the drawings.

In the drawings, the numeral 1 is used to designate any suitable form of a supporting base, and 2 a casing or outer shell held thereto. Preferably, the casing or shell is cylindrical in form and composed of any suitable material, preference being given to glass. At its lower end the casing or shell 2 is seated on a shoulder or supporting ledge 3 of a block 4 fitted within the ring flange 5 of the base 1, the said block being provided with a seat 6 for the reception of an expansible packing ring 7.

From the base 1 projects a bracket 8, to 50 which is secured an upwardly extended stud 9 carrying a handle piece 10, and to the

upper screw-threaded end 9' of the stud or handle post 9 is secured by means of a nut 10' the outer end of an arm or bracket 11. This bracket at its outer end carries a securing ring 12, which fits over the upper 60 end of the casing or shell 2 and holds the same properly positioned relative to the base section 1. The brackets, handle piece and base form a holder for the outer container or shell of the heater.

Through the arm or bracket 8 extend the current wire connections $a-a'$, which connect respectively with the terminal posts $b-b'$ upwardly extended through the supporting block 4. On the said block 4 is seated a coil holding block 13, the terminal posts $b-b'$ extending upwardly through bores $c-c'$ in the block 13 and projecting within an annular groove 13' of the said block. Within the said annular groove 13' is seated a resistance coil 14, the ends of which connect with the terminal posts $b-b'$ of the connections $a-a'$.

Through the base 1 and a vertical bore 14^a in the block 4 extends a clamp screw 14', the inner threaded end of which works within a countersunk threaded seat 15 of the block 13, which block rests on the packing ring 7. When the clamp screws 14' are tightened during the assembling of the parts 80 the block 13 is drawn downwardly toward the block 4, compressing the packing ring 7 to expand the same firmly against the inner wall surface of the lower end of the casing or shell 2 and by so doing making a 85 closed or hermetical sealed union joint between the parts, the joint between the block 4 and the clamp screw 14' being closed by the ring washer 15' interposed between the blocks 4 and 13.

On the projecting end portion 16 of the bracket 8 is slidably mounted a slotted sleeve 16', carrying a socket plug 17, said sleeve being normally held outwardly pressed by the pressure of the spiral spring 17' mounted on the end portion 16 of the bracket 8 and bearing against the inner end of the sleeve 16'. From the end portion 16 of the bracket 8 project the contact posts 18 and 18', which on the socket plug 17 being forced inwardly fit within the seats 19 and 19' thereof for making contact with the terminals of the electrical supply wires or connections 20 and 20' extended into the switch or socket plug 17 to close the circuit to the resistance coil 14. 100 105 110

The sleeve carrying the socket plug 17 is held inward by pressure exerted on the finger piece extensions d , d' , projecting respectively from the bracket extension 16 and 5 the plug 17, and while the extensions d and d' are held together manually the current flows through the coil 14. The moment pressure is released or removed from the switch or socket plug 17, the pressure of the 10 pressed spring 17' forces outwardly the sleeve 16' to take the contact posts 18 and 18' from within the seats 19 and 19' and by so doing breaking the electrical circuit.

The casing or shell 2 contains and holds 15 the liquid or fluid to be heated, but where the heater is employed for heating milk or food products, the same is placed in a container or auxiliary vessel 20^a which is placed into the casing or shell 2 and partly sub- 20 merged within the liquid contained therein. This liquid is heated by the resistance coil 14 on the electrical circuit being closed, and said liquid in turn transmits its heat energy to the partly submerged container or aux- 25 illiary vessel 20^a for heating the contents thereof, the said container or vessel 20^a being held securely in place by means of a packing ring 22' attached to the securing ring 12.

30 The described heating device will be found not only convenient for use generally, but more especially so in connection with sick rooms, hospitals and for use in the heating at night time—the milk or food product for 35 babies; the device being extremely light and easily moved from place to place and the electrical connection being at all times under the control of the person using the same, the device is exceedingly useful in households 40 and all places wherein it is required to quickly and economically heat liquids and food products.

Inasmuch as the improved heating device 45 may be quickly taken apart and the parts re-assembled, access may be had at all times to the various essential parts for the cleaning thereof, thereby making a sanitary heater for the purposes desired.

I am well aware that changes may be made 50 in the details of construction of the parts herein shown and described without creating a departure from the spirit and scope of the invention, and I do not wish to be understood as so restricting and limiting the invention, the essential feature of which comprises a heating unit provided with a resistance coil for the heating of liquid, the 55 said heating unit being detachably secured within an open mouth outer shell or casing.

60 Having thus described the invention what is claimed as new and desired to be protected by Letters Patent is:—

1. In an electric liquid heating device, the combination with a holder, of an open mouth 65 container or shell detachably held thereto, a

heating unit provided with a resistance coil situated within said container or shell adjacent the bottom portion thereof, a packing interposed between the heating unit and the shell for the making of a tight joint connection between the same, electrical connections extended through the holder and connected with the resistance coil of the electrical unit for passing an electrical current through said coil, and a switch member in the electric circuit for controlling the flow of the electrical current to the resistance coil. 70 75

2. In an electric liquid heating device, the combination with a holder, of an open mouth container or shell detachably held thereto, a packing joint union between the lower end of the container and the holder, a heating unit provided with a resistance coil situated within the said container and detachably held therein against movement, and electrical connections extended through the holder and connected to the said resistance coil within the container. 80 85

3. In an electric liquid heating device, the combination with a holder, of an open mouth container or shell held thereby, a heating unit provided with a resistance coil within the said container or shell, means for detachably securing the heating unit within the container, a packing ring interposed between the heating unit and the bottom of the holder for making a tight joint with the container on the expansion thereof, electrical connections extended through the holder and connected to the resistance coil of the heating 90 95 unit, and a switch member interposed in the electric circuit for controlling the opening and closing of the circuit to the resistance coil. 100

4. In an electric heating device, the combination with a holder, of an open mouth container or shell detachably held thereto, a packing joint connection between the lower end of the container and the said holder, a heating unit provided with a resistance coil situated within the container and detachably held therein against movement, electrical connections extended through the holder and connected to the said resistance coil within the container, and pressure controlled means interposed within an electrical circuit for making and breaking connection with the resistance coil of the heating unit. 105 110 115

5. In an electric liquid heating device, the combination with a holder, of an open mouth container detachably united to and held thereby, a heating unit provided with a resistance coil situated within the container and interposed between the said container and the holder and held in position by the container, and means for controlling the flow of an electrical current through said resistance coil. 120 125

6. In an electrical liquid heating device, 130

the combination with a holder, of a supporting block, an open mouth container supported by said block, a packing ring connection between the block and the container for the
5 making of a tight joint, of an electrical heating unit provided with a resistance coil situated within the container, means for holding the supporting block to the bottom of the holder and detachably uniting the
10 heating unit to said block, electrical connections extended through the holder and connected to the resistance coil, and a switch member interposed within the said connection for making and breaking the electrical
15 circuit.

7. In an electrical heating device for the described purpose, the combination with a holder, of an open mouth container detachably held thereto, a heating unit provided
20 with a resistance coil detachably held within the container against movement, connection between said heating unit and a source of electrical supply, and controlling means introduced within the said connection for
25 making and breaking the electrical current to the said resistance coil.

8. In an electric liquid heating device, the combination with a holder provided with a supporting base, an upwardly projected handle and a forwardly projected securing ring extended from the upper portion thereof, of an open mouth container fitted through the securing ring and detachably united to the base portion of the holder, a heating unit provided with a resistance coil detachably secured within the container against movement, a packing joint connection between the lower end of the container and the supporting base of the holder, connections between said heating unit and a source of electrical supply, and controlling means interposed within said connection for making and breaking the electrical connection with the resistance coil of the heating unit.

In testimony whereof I have signed my name to this specification in the presence of two subscribing witnesses.

MILTON H. SHOENBERG.
